UNITED STATES PATENT OFFICE

ARTHUR A. JOHNSON, OF BRIDGEPORT, CONNECTICUT

MANIFOLDING

Application filed October 25, 1929, Serial No. 402,408. Renewed September 29, 1931.

This invention relates to manifolding, and more particularly, to a pile of manifolding material made up of a plurality of continuous worksheet strips, each having a succession of forms, and a carbon strip interleaved between each two adjacent worksheet strips.

Heretofore, it was proposed to have such worksheet strips and carbonsheet strips secured together at intervals along the strips by staples or other means so as to hold the strips in registration preparatory to and during the operation of writing upon a pile of strips; and it was also proposed to have the securing means so located that it would hold the written set of forms together in booklet form for subsequent writing operations or for handling. In one of such previous proposals, the forms were transversely perforated between the body thereof and the secured portion so as to permit the inside leaves of the booklet to be removed as desired and without necessitating the removal of the outside leaves, or any of the other leaves, but allowing a stub to remain attached to the other leaves.

An object of the present invention is to provide a manifolding pack in which the strips are so secured together that the leaves in the booklet, resulting from severing a set of forms from the continuous pile, may be removed at will without disturbing any of the other leaves and without necessitating the provision of the transverse line of perforations and permitting the entire form to be kept intact.

This is accomplished, according to the present invention, by providing staples in the pile of worksheets—one located so near one edge of each set of forms that by pulling on the lower edge of the form to be removed, the material of the form between the legs of the staples and the adjacent edge of the form will be slit to permit the form being removed to slip by the staple. The

staple is preferably placed longitudinally of the strip so that the two legs of the staple lie in the same longitudinal line and, hence, only one slit need be made to permit removal of the form.

Another feature of this invention is the provision of means for facilitating the formation of the slit by the pulling action on the form to be removed, and this is accomplished by providing a weakened line or lines of perforations running from the legs of the staple to the adjacent edge of the form. When this is done, the staple may be placed further from the edge of the form than without it, and it is preferable that the staple be placed longitudinally of the strip, for then only one line of perforations communicating with the edge of the strip need be provided instead of two which would be used in case the staple is located transversely of the strips.

Other features and advantages will hereinafter appear.

In the accompanying drawings which illustrate one form of the invention, that at present preferred—

Figure 1 is a perspective view of a manifolding pack made in accordance with the present invention.

Fig. 2 is a longitudinal section taken through the pile of worksheets of which the pack shown in Fig. 1 is formed.

Fig. 3 is a transverse sectional view taken on the line 3—3 of Fig. 2, and showing the means for holding the pile of strips together.

Fig. 4 is a similar transverse sectional view taken on the line 4—4 of Fig. 2.

Fig. 5 is a perspective view indicating the manner in which an intermediate leaf of the booklet may be removed by hand without removing the other strips.

Fig. 6 is a detail view showing the two lines of perforations which may be used when the staples are placed transversely of the strips.

Fig. 7 is a similar view, showing the position which the staple may occupy with refer-

ence to the adjacent edge of the form when the communicating line of perforations is not used.

As shown in the accompanying drawings, 5 the manifolding pile of the present invention comprises a plurality of superposed worksheet strips 10 each of which may have a continuous succession of printed forms 11. Interleaved between each two adjacent worksheet strips 10 is a carbon strip 12 so that 10 writing performed on the top strip 10 will be reproduced on the under strips 10 through the medium of the carbon strips 12.

To receive said writing operations, the 15 worksheet strips 10 are placed in proper superposed relation, one above the other, with the printed forms 11 on one strip registering with those of the other strip or strips.

To hold the worksheet strips 10 in said 20 proper superposed registering relation and to hold the carbon strips in their proper positions relative to the worksheet strips after the strips are superposed, they are secured together by means placed at intervals along 25 the pile of strips.

According to the present invention, these means comprise staples 13 which extend through all the strips of the pile and have their legs 14 bent over at one side to hold 30 the staples in place against unintentional removal. These staples hold the strips together preparatory to and during the operation of writing upon the strips.

After a set of forms has been written upon, 35 as, for instance, in a typewriting machine, the set is severed from the next set in the pile along lines of perforations 15 separating one form on each strip from the next.

Heretofore, it was proposed to locate the 40 staple 13 on the lines of perforations 15 so that the staple would become inoperative to hold the strips together after the written set was severed from the pile.

In some classes of work, however, it is desirable to keep the severed set intact, at least 45 temporarily, until certain data, which can only be obtained after the writing operation, has been filled in—say, for instance, in the spaces 16 on the kind of form illustrated 50 herein. Some of this information is written on all of the strips of the set, after which the set of strips while still intact is transferred from one person to another interested in the transaction and these persons make 55 their notations on certain of the strips and usually remove one or more of the strips for their own information and use.

In some cases it is possible to arrange the 60 forms in consecutive order in the sets so that the first form to be removed is either at the bottom or the top, and the next form to be removed is next to it and so on. But, 65 since certain of the data should be filled in by one person or another in the sequence, this arrangement is not always convenient,

for it requires duplication of work in separately filling out two forms which cannot lie adjacent each other in the pile if they do lie in desired sequence.

To obviate this difficulty, the present invention provides means for permitting the removal of any one of the forms in the set or booklet, which results from the severing of one set of forms from the next, without necessitating the removal of any of the other forms and permits the removal of the form desired in its entirety instead of allowing a stub to remain with the set as was heretofore proposed.

This is accomplished by the present invention by providing the staples 13 at the head of the forms constituting a set in such a way that one or more slits are produced between the point at which the staple is located and the adjacent edge of the form when the form to be removed is grasped and pulled from the booklet. This may be done as shown in Fig. 7 by placing the staple 13 so close to the adjacent edge 18 of the form that when the form is pulled a slit is torn in the form by the legs 14 of the staple, so that the form to be removed may slip by the staple when pulled. The staple may be placed transversely of the sheet, in which case each leg 14 would produce a slit, but it is preferable that it be placed longitudinally of the form so that the legs of the staples will produce only one slit.

The forming of the slit through which the staple legs may pass during the extraction of one form may be facilitated by producing weakening lines between the points where the legs of the staple are located and the adjacent edge 18 of the form or leaf, as, 100 for instance, the lines of perforations 17 illustrated in Figs. 1, 2 and 6 herein, so that when the form to be extracted is pulled, the fabric of which it is constituted will break down between the perforations 17 and easily 105 form a slit permitting the form to slip by the staple.

In this case also, the staple may be placed transversely of the form as shown in Fig. 6, in which case, however, two lines of perforations 17 leading from the legs 14 of the staple extend to the adjacent edge 18 of the form. It is therefore preferable that the staple lie longitudinally of the strip as 110 shown in Figs. 1 to 4, for then only one line of perforations 17 need be provided.

When the forming of the slit in the leaf to be extracted is facilitated by the preparation of the forms with the perforations 17, 115 the staple may be set inwardly farther from the edge 18 of the form than otherwise, and the leaves, particularly the upper and lower leaves, are therefore less likely to be accidentally torn from the booklet when the em- 120 130

bodiment of the invention illustrated in Figs. 1 to 4 is employed.

As illustrated in Fig. 2, the line of perforations 17 extends to the leg 14 of the staple 5 which is most remote from the line of severance 15 so that at the beginning of the extracting operation, both legs of the staple tear through the ties 19 between the perforations 17 in causing the slit to be formed 10 from the point of location of the most remote leg 14 to the edge 18 of the form.

Other variations and modifications may be made within the scope of this invention 15 and portions of the improvements may be used without others.

Having thus described the invention, what is claimed as new and for which it is desired to obtain Letters Patent, is:—

1. A manifolding pile comprising a plurality of continuous worksheet strips each having a succession of forms separated by lines of severance; a continuous carbon sheet interleaved between each two adjacent worksheet strips; means located at intervals along the pile of superposed strips for securing all of the strips of the pile together in desired relation with the lines of severance and the forms of the several strips in registration before and after the severance of a set of forms, 20 said means being located near an edge of a severed set of forms and weakening lines extending from said strip-securing means to the adjacent edge of the forms for causing slits to be formed by the securing means to the adjacent edges of the forms, thereby permitting a form to slip by the securing means when pulling force is exerted on the form to be removed from the severed set.

2. A manifolding pile comprising a plurality of continuous worksheet strips each having a succession of forms separated by lines of severance; a continuous carbon sheet interleaved between each two adjacent worksheet strips; means located at intervals along the pile of superposed strips and passing therethrough for securing all of the strips of the pile together in desired relation with the lines of severance and the forms of the several strips in registration before and after the severance of a set of forms, 45 said means being located near said lines of severance; and weakening lines extending from said strip-securing means to the adjacent lines of severance for causing slits to be formed by the securing means to the adjacent edges of the forms to thereby permit the form to be removed from the severed set to slip by the securing means when pulling force is exerted on the forms.

3. A manifolding pile comprising a plurality of continuous worksheet strips each having a succession of forms separated by lines of severance; a continuous carbon sheet interleaved between each two adjacent work-

sheet strips; staples located at intervals along the pile of superposed strips for securing all of the strips of the pile together in desired relation with the lines of severance and the forms of the several strips in registration before and after severance of a set of forms, 50 said staples being located near said lines of severance; and weakening lines extending from the legs of the staples to the adjacent lines of severance for causing slits to be formed by the legs of the staples to the adjacent edges of the form to thereby permit the forms to slip by the staples when pulling force is exerted on the form to be removed from the severed set.

4. A manifolding pile comprising a plurality of continuous worksheet strips each having a succession of forms separated by lines of severance; a continuous carbon sheet interleaved between each two adjacent worksheet strips; staples located at intervals along the pile of superposed strips for securing all of the strips of the pile together in desired relation with the lines of severance and the forms of the several strips in registration before and after severance of a set of forms, 55 said staples being located near said lines of severance and substantially parallel thereto; and weakening lines extending from the legs of each staple to the adjacent line of severance for causing slits to be formed by the legs of the staples to the adjacent edges of the forms to thereby permit the form to slip by the staples when pulling force is exerted on the form to be removed from the severed set.

5. A manifolding pile comprising a plurality of continuous worksheet strips each having a succession of forms separated by lines of severance; a continuous carbon sheet interleaved between each two adjacent worksheet strips; staples located at intervals along the pile of superposed strips for securing all of the strips of the pile together in desired relation with the lines of severance and the forms of the several strips in registration, 60 said staples being located near the lines of severance and each having its legs arranged in line longitudinally of the strips; and a weakening line extending from said staple to the adjacent line of severance for causing a slit to be formed by the legs of the staple to the adjacent edge of the form to thereby permit the form to slip by the staple when pulling force is exerted on the form to be removed from the severed set.

6. A manifolding pile comprising a plurality of continuous worksheet strips each having a succession of forms separated by lines of severance; a continuous carbon sheet interleaved between each two adjacent worksheet strips; wire staples located at intervals along the pile of superposed strips for securing all of the strips of the pile together in desired relation with the lines of severance and the forms of the several strips in regis- 125

tration before and after the severance of a set of forms, said staples being located in close proximity to the lines of severance and each having its legs arranged in line longitudinally of the strips so as to cause a single slit to be formed by the legs of the staple to the adjacent edge of the form to thereby permit the form to slip by the staple when pulling force is exerted on the form to be removed from the severed set.

5 Signed at Bridgeport, in the county of Fairfield and State of Connecticut, this 24th day of October, 1929.
